UNITED STATES PATENT OFFICE

159,648

SOCK OR SIMILAR ARTICLE

Lionel Lasar, Forest Hills, N. Y.

Application May 14, 1949, Serial No. 2,663

Term of patent 3½ years

(Cl. D47—7)

To all whom it may concern:

Be it known that I, Lionel Lasar, a citizen of the United States of America, residing at Forest Hills, in the county of Queens and State of New York, have invented a new, original, and ornamental Design for a Sock or Similar Article, of which the following is a specification, reference being made to the accompanying drawing, forming a part thereof.

Figs. 1 and 2 are respective side views of a sock or similar article, showing my new design.

I claim:

The ornamental design for a sock or similar article, substantially as shown.

LIONEL LASAR.
